UNITED STATES PATENT OFFICE.

RALPH S. MEGATHLIN, OF SOMERVILLE, MASSACHUSETTS, ASSIGNOR TO UNITED SHOE MACHINERY CORPORATION, OF PATERSON, NEW JERSEY, A CORPORATION OF NEW JERSEY.

MODEL MAKING.

1,417,274.

Specification of Letters Patent. Patented May 23, 1922.

Application filed August 1, 1921. Serial No. 488,860.

To all whom it may concern:

Be it known that I, RALPH S. MEGATHLIN, a citizen of the United States, and residing at Somerville, in the county of Middlesex and State of Massachusetts, have invented certain Improvements in Model Making, of which the following description, in connection with the accompanying drawings, is a specification, like reference characters on the drawings indicating like parts in the several figures.

This invention relates to last making and is illustrated in connection with the production of a set of lasts or, more exactly, models.

It is the present custom to turn lasts in a last lathe, which is one form of the copying lathe, using a model which is reproduced in the work. The machine is provided with two substantially pantographic mechanisms called graders to modify the longitudinal and lateral dimensions of the model as desired, independently. It being required to turn a set of, for example, women's lasts comprising a regular run of sizes and widths from a single model, the fundamentals of the grading are substantially as follows:

The lasts having the same nominal "width," that is, the 4-B (model), 1-B, 5-B, 6-B, etc., are substantially geometrically similar solids, increasing $\frac{1}{3}$ inch in length and $\frac{1}{4}$ inch in perimeter at the waist for each length size unit. These increments will be found to result in a substantially uniform rate of increase in all directions, though there may be actually a small discrepancy between the length and width magnification factors, and the discrepancy varies somewhat, owing to the custom of making lasts of the same marked size of various actual lengths to secure differences in style of toe tip.

The lasts having the same length number, as the 4-B, 4-C, 4-D, etc., vary in perimeter at the waist by $\frac{1}{4}$ inch per size in width.

All these lasts being placed in proper tread relation to a horizontal plane, the lateral magnification will cause their toe tips and heels to come at varying distances from the plane. In other words, their toe springs and heel springs have been altered by the magnification from the original model. This condition of things is undesirable for several reasons, among which are;

(1) Human feet do not vary in size and

form in this manner, and the lasts fail to fit equally well throughout the series.

(2) The appearance of different shoes of the set varies so much as to affect disadvantageously the retailing problem.

(3) The differences in height and wedge of heel required throughout the set constitute a serious shoe manufacturing difficulty.

This general problem is dealt with in various ways, according to the expense to which the shoe manufacturer is willing to go.

The best solution of it in general use, prior to the present invention, involves making one or more (generally three) models in each width, for example, a 1, 4 and 7 in each width. These models are corrected,

after being produced by grading in the last lathe in the ordinary way, by bending them at the waist or the ball, to change the relation between the toe tip, heel corner and ball point, in order to correct the springs and make the whole series more uniform. This is done by splitting the last from the top and bottom so deep that the slits nearly meet, and wedging one slit until the other closes. This whole operation has to be performed by a skilled model maker, and is entirely empirical. It is very expensive, cannot be done certainly twice alike, and at its best, only a small fraction of the lasts in the set are right, since all the lasts graded from these corrected models, that is, those which are not duplicates of them, will be affected with the original difficulty, only to a smaller extent.

It is an important object of the present invention to provide a solution for this problem which will be more economical than the present practice, practically satisfactory, and which will avoid the objections mentioned, among others. I contemplate turning the entire set of lasts from a set of modified models, all of the same foot room, but having their toes attached to the main body at varying angles, these angles being accurately

chosen so that the standard model thus modified will, in each case, grade exactly into the last which it is desired to produce with it.

A model and, indeed the entire set of models thus characterized form important features of the invention. The members of the set will all measure the same size and width but the line joining the toe tip and ball tread point will make varying angles

with the line from the ball tread point to the heel corner, throughout the set. In the illustrated embodiment of the invention a set of preferably interchangeable toe pieces 5 is used, attached to the main body at varying angles, and such a set of apparatus forms an important feature of the invention. The invention also provides a definite systematic way of ascertaining predeterminedly the required angles of bend in the standard (4-B 10 for women's) model in order to produce the desired results, and accordingly the improvement in methods of last production which consists in ascertaining the required model 15 distortion, distorting the model correspondingly and then grading directly from the distorted model to produce the result desired, constitutes an important aspect of the invention.

20 These and other aspects of the invention will be better understood from the following description of a preferred embodiment thereof taken in connection with the accompanying drawings, in which,

25 Fig. 1 illustrates diagrammatically the model and its set of toe pieces.

Fig. 2 is a diagram showing generally how to determine the bending angles of the models.

30 Fig. 3 is a diagram showing how to determine the bending angles for the special case of lasts of the same width.

Fig. 1 shows diagrammatically a model 10 have a secant face 13, preferably at or 35 about the waist, to which various toe pieces 11, 12 shown in dotted lines may be firmly attached in any desired or convenient manner. These toe pieces are equal in number 40 to the models which are to be used to develop the whole system of lasts, and are built on to the original model waist at varying angles such that when graded they will yield the result desired.

The single waist and back part and the 45 set of toe pieces are thus the equivalent of a like number of models with corrected 50 spring. I shall show herein how these toe pieces may be developed accurately and systematically without the expense of the skilled model makers judgment, the proper 55 angles of cut for the toes being determined by analytic rather than empirical methods. This set of model apparatus I regard as an important feature of the invention.

55 Fig. 2 is a diagram developing the general solution of the bending problem.

PSKIHCRQ is the central vertical longitudinal section of the original model, and B is the bending point, taken arbitrarily. 60 TQD is the floor line. BT is (here) drawn from B through the toe tip P to meet the floor line in some point T. In some instances it may be well to draw BT so as to 65 pass a little above or below P, as a certain amount of toe spring variation can be ac-

ted in this way as will be seen. In Fig. 2 the model is bent by swinging the toe tip down about the point B, through an angle γ . The figure TPSQR then takes the position $T_1P_1SQ_1R$, and the angle of bend, γ , is TBT_1 . The line T_1H_1 is taken as the axis of rotation in the lathe. This line does not pass through the toe tip P_1 in the drawing, owing to the fact that the last shown has an actual toe spring, and the analysis is much simplified by working from the point T_1 , instead of the toe tip. However, slight variations in positions of models on their mechanical axes of rotation frequently occur in practice, as it is difficult to 70 pick out any definite location for the heel dog. If the length and width grading factors are equal, it makes no difference at all. If they are not, in theory a slight distortion results from such a tipping, but is 75 never noticed in practice.

The bent model P_1H_1 will now be graded, using, however, T_1 as a fixed origin. The length grading factor will be called L, and the width grading factor W. The graded 90 position C' of any point C is found by finding its projection E on the axis T_1H_1 , taking $T_1E' = Lx(T_1E)$, and erecting the perpendicular $E'C' = Wx(EC)$. The floor line may be located by the points G_1 and G' in 95 the same way, and all desired points of the last similarly plotted.

From the above it is obvious that

$$\tan s = \frac{W}{L} \tan r \quad (1) \quad 100$$

The heel spring of the graded last is $C'D'$ (not parallel to CD_1), and

$$C'D' = T_1E' \sin s - E'C' \cos s \quad (2) \quad 105$$

$$= Lx(T_1E) \sin s - Wx(EC) \cos s$$

Now take TEH as the axis of the original unbent model. TH must be of the same length as T_1H_1 in order to bring out the length grade, and is easily seen to be near enough. Since the heel of the last is on a curve, EH and EH_1 will be sensibly equal, and as already stated, a small variation in position of the axis in a model is of small moment. In the drawing the angle TBT_1 is exaggerated, and the distance HH_1 is really very small. The difference between TE, T_1E , is also negligible. This artifice simplifies the analysis, and involves no error 110 of importance in wood work. 115

In effecting a direct solution of the problem, the known elements are L, W, the distances $TE = T_1E$, EC, all data relating to the point B, such as the distances TB, BE, and angle TBE, the angles $t = BTQ$ 125 $= BT_1Q_1$ and the original model heel spring CD.

(It should be noticed that we do not know TE and EC and the angle TBE exactly at first, since E is the foot of the per- 130

pendicular from C to the bent model axis T_1H_1 , which is not yet known. But the angle TET_1 will be small, and the distance TE as found by projecting C on the original model axis can be accepted for a first approximate calculation, (and will often be near enough), or can be corrected in advance in the light of experience. EC can be accepted as measured on the original model. It may be remarked at the same time that we have described T_1 as swung from T around B, and also called $TE=T_1E$. Practically the error involved in this is not discernible in woodwork. Any necessary allowance could be made in the sawing for the separable toe-piece, in order to bring out the overall lengths the same.

By means of equation (2) in which everything on the right is known except s , we can determine the angle s so as to make the graded heel spring $C'D'$ anything we like, for example equal to the original CD . This equation can be solved by "trial and error" with a table of natural or logarithmic sines and cosines, or reduced to algebraic form by the substitution

$$\sin = \sqrt{1 - \cos^2}$$

Having determined s we can determine the angle r by the equation (1).

The angle z is then given by

$$z = t - r. \quad (3)$$

In the triangle T_1BE we now know T_1E , BE , and z ; and

$$\sin T_1BE = \frac{\sin z}{BE} T_1E \quad (4)$$

The angle TBE is known by the initial assumption as to the location of the point B, and the angle $y = TBT_1$ is therefore given by

$$y = 360^\circ - T_1BE - TBE \quad (5)$$

which is the result sought.

The toe spring of the original model PH has been altered slightly by the grading, due to the facts that the point P_1 is not on the grading axis T_1H_1 , and that the angle of the floor line with this axis is changed by the grade. A proper arrangement of the line BT in regard to the point P, in the light of experience, will effect a certain amount of control of this feature. In the example of Fig. 2, both of the enumerated causes increase the toe spring of the graded last. If the line BT had been drawn above the point P to such an amount that the point P_1 would have fallen below T_1H_1 , the toe spring could have been kept unchanged.

The simpler special problem of the set of lasts having the same "width" will now be developed. As already stated, these lasts are substantially geometrically similar solids. Any one can therefore be developed from the model by selecting a point as a pole, and magnifying all radii vectors drawn

from the point to the model surface, in the same proportion. In the actual cutting of such a last in the lathe, the longitudinal and lateral magnifications are entirely independent and at right angles to each other, but under our fundamental (and somewhat inaccurate) hypothesis, the result is substantially as stated.

Fig. 3 shows at $abcdefg$ the central longitudinal profile of the 4-B model. We are to determine how to bend it in order that the bent 4-B model will grade into another required B last. We first select the axis of the bend. (This point B, here, as well as the general problem, is preferably always taken in the waist at a place where the upper and lower contours are about parallel, as bending the model about this point will not tend to cause troublesome "steps" at b and f on the upper and lower surfaces.) In Fig. 3 the point B selected is on the line oae , joining the toe tip a and lower heel corner e . The floor line is shown at oh , the toe spring at at , and the heel spring at eh . ee' is drawn parallel to the floor line. The graded last should have its lower heel corner on this line in order to preserve the overall heel height unchanged.

Let G be the magnification factor. Locate e' on ee' so that $oe' = Gx(oe)$. Locate e_1 on oe' so that $oe_1 = oe$. In the drawing G has been grossly exaggerated in order to make the drawing clear. Its value is approximately 1.35, which would grade a 4-B up to about a 14-B. Even with this exaggeration Be and Be_1 would differ only by about .02 inch on a full size scale, so that we can assume that $Be = Be_1$.

If, then, we bend down the body of the last about the point B, leaving the toe in position, the distorted last takes the position $abc_1d_1e_1fg$. Magnify the distorted last by the factor G , which can be done by multiplying all radii vectors through O by G , and the magnified last will take the position $a'b'c'd'e'f'g'$ and will obviously have the same overall heel height as the original model $abcdefg$. The toe spring, at , has been changed to $a't'$. This discrepancy is small; is exaggerated in the drawing like everything else, and on the shoe itself will be hardly noticeable.

The angle of bend is eBe_1 , and has thus been found graphically. If e'' is the point where eh cuts oe' , this angle will obviously differ from eBe'' by an amount too small to be measurable on wood and $e''h = e_1h_1$ within a like degree of accuracy. The value of eBe'' is easily found. Let $X' = e'h'$, the desired overall heel height, and let $X = eh$, the model overall heel height. Then $e_1h_1 =$

$$e''h = \frac{X'}{G} \quad \text{and} \quad ee'' = X - \frac{X'}{G}.$$

Be is known and may be called F, and the angle Be'' , 130

which may be called ϕ , is known from the original data of the last. Applying the trigonometric formula

$$5 \quad \cot A = \frac{1}{\sin C} \left[\frac{b}{a} - \cos C \right]$$

we have

$$10 \quad \cot eBe'' = \frac{1}{\sin \phi} \left[\frac{F}{X - \frac{X'}{G}} - \cos \phi \right] \quad (6)$$

It will be noticed that nothing in the above analysis depends upon the point e being the lower heel corner, so that it has really been shown how to bend the model so as to maintain the height of any point of the tread surface unchanged when grading a last from another of the same marked width. The formula (6) is also true generally for cases where X' and X are not equal. Similarly the results developed in regard to Fig. 2 are equally general, except that the initial approximations relative to the position of the point E are weakened by moving C toward the toe. The process, in brief, is to plot the desired result, which is simple when the magnifying factor is the same in all directions, grade it inversely in order to obtain the model which must be directly graded from in order to produce it, and compare this model with the originally given model.

The formulae developed above determine the angles through which the original 4-B model must be bent in order to grade into a last having the desired sole profile. The proper number of 4-B models may be prepared by duplication of the first one in the last lathe, their toes cut off in accordance with these angles and joined to back parts (Fig. 1) corresponding to the zero angle of cut. If the joining means is separable, one back part will serve for the whole series, but the speed ordinarily necessary in getting out a last order will require the use of several machines at once.

These models are produced without the expensive skilled-labor-cut-and-try method, the work is predeterminedly exact, and can be duplicated exactly at any future time. Models can be made corresponding to every size and width, so that a perfectly accurate set of lasts can be produced.

Having described my invention, what I claim as new and desire to secure by Letters Patent of the United States is:—

1. That improvement in methods of manufacturing lasts which consists in providing a set of models all of the same style, size and width, but having their forward and rearward portions joined at varying angles, and cutting lasts from these models in the last lathe, by means of the length and width graders.

2. That improvement in methods of manu-

facturing lasts which consists in turning in the last lathe, by ordinary length and width grading, a last of desired size and width from a model distorted by the introduction of a bend calculated to modify the effect of the grading upon the sole profile of the normal model.

3. That improvement in methods of manufacturing lasts which consists in turning in the last lathe by ordinary length and width grading, a last of the desired size and width from a model having an abnormal relation between the toe tip, heel corner and ball point, to modify the effect of the grading upon the sole profile of the normal model.

4. A set of model apparatus comprising a standard rear part and a set of toe parts identical except for a varying wedge at their rear ends, and all constructed and arranged to fit the rear part.

5. A set of model apparatus comprising a standard rear part, a standard toe part, and a set of other parts identical with one of said parts except for the addition or subtraction of wedges of varying angularity at the joints, all the members of the set being constructed and arranged to fit the standard part of differing species to form a bent model.

6. A last part constructed and arranged to fit interchangeably a set of last parts of complementary species to form a set of variably bent models of the same size and width.

7. A set of last models of the same size and width differing among themselves by a systematic series of bends, whereby any one of the set can be directly length-and-width-graded in the last lathe to produce a last of a predetermined profile characteristic.

8. A last model of standard size and width differing from the standard model of that style by a bend between its forward part and its rear part, the bend being determined in connection with an assumed grade to produce a graded last having a predetermined profile characteristic.

9. A last model of standard size and width differing from a standard model of that style by a bend determined substantially in accordance with formula (5) of the annexed specification.

10. That improvement in the art of producing from a model a graded object having anomalous variation from an object regularly graded from the model, which consists in plotting an anomalous graded result desired, grading it inversely, distorting the model to correspond with the inversely graded object, and then grading from the distorted model directly to the object desired.

In testimony whereof I have signed my name to this specification.

Certificate of Correction.

It is hereby certified that in Letters Patent No. 1,417,274, granted May 23, 1922, upon the application of Ralph S. Megathlin, of Somerville, Massachusetts, for an improvement in "Model Making," errors appear in the printed specification requiring correction as follows: Page 1, line 77, for the word "splitting" read *slitting*; page 2, lines 93, 94, 105, and page 3, line 95, strike out the letter "x" and insert the multiplication sign $\times$; and that the said Letters Patent should be read with these corrections therein that the same may conform to the record of the case in the Patent Office.

Signed and sealed this 7th day of November, A. D., 1922.

[SEAL.]

KARL FENNING,

Acting Commissioner of Patents.
